Blackmore, Spencer & Hart.

ATTORNEY

UNITED STATES PATENT OFFICE.

ROSCOE BERINGER, OF DETROIT, MICHIGAN, ASSIGNOR TO GENERAL MOTORS CORPORATION, OF DETROIT, MICHIGAN, A CORPORATION OF DELAWARE.

CONVERTIBLE BODY.

Application filed November 17, 1924. Serial No. 750,356.

This invention relates to convertible bodies for automobiles and is illustrated as embodied in a construction including a top mounted on a body in such a manner that the space below the top can be closed, when desired, by novel glass panels. The principal object of the invention is to provide a convertible body of this character which is especially pleasing in appearance both when open and closed, and in which the handling of the panels is facilitated.

The various features of novelty, which are more fully discussed below, include improved means for clamping the panels in place 15 on top of the doors of the body; an arrangement permitting the use of panels the full width of the doors so that there is no pillar required between the doors, especially when taken in combination with an arrangement 20 for housing the panels in the doors themselves when not in use in spite of the fact that they are as wide as the doors; an improved construction in the panel itself permitting the use of a narrow metal frame which does not 25 materially obstruct the driver's vision; as well as a novel arrangement of weather strips and a sub-assembly seat unit carrying a door post of improved construction.

These various features, and other desirable 30 details of construction, will be apparent from the following description of the illustrative embodiment of the invention shown in the accompanying drawings, in which:

Figure 1 is a side elevation of the improved 35 convertible body when closed;

Figure 2 is a similar view of the body when open, partly broken away to show the way in which the two doors conceal the door post between them;

Figure 3 is an inside elevation of one of the 40 doors and its panel, partly broken away to show the manner of housing the panel inside of the door when not in use;

Figure 4 is a vertical section on the line 45 4-4 of Figure 3 showing the mounting of the panel on the top of the door;

Figure 5 is a plan view of the door on the line 5-5 of Figure 3;

Figure 6 is an enlarged outside elevation

of one upper corner of the door, broken away 60 to show part of the means for locking one of the supporting posts of the panel;

Figure 7 is a vertical section on the line 7-7 of Figure 6 showing part of the means for locking the supporting post; 55

Figure 8 is a vertical section on the line 8-8 of Figure 3 showing one operating mechanism for the post locking means;

Figure 9 is a similar view of a different 60 form of operating mechanism; and

Figure 10 is a horizontal section on the line 10-10 of Figure 1 showing the novel concealed door post.

In the arrangement selected for illustration 65 the invention is embodied in an automobile body including a body 20 and a top 22, preferably of the type known as a permanent top. The space between the body and the top rear of the doors is closed, when desired, by a glass panel 24, which may be of any desired type. 70

In order to do away with the necessity for any pillar between the windshield and the rear end of the top, as has been usual in previous convertible bodies, I provide a novel 75 sub-assembly including the front seat 26 to which is secured on opposite sides, door posts 28 shown as having flanges 30 to be secured to the vehicle frame to fasten the sub-assembly in place. The doors 32 and 34 are hinged, respectively, at their front and rear edges and 80 at their adjacent meeting edges are rabbeted out in any desired manner, as for example, for forming projecting flanges 36 (Fig. 10) at their edges, which flanges overlap and conceal the corresponding door post 28. By this 85 arrangement there is apparent to the eye only a single line between the two doors on the same side of the body. In order to preserve the neat appearance given by this arrangement the panels 38 and 40 for these doors are 90 the same width as the doors. Thus when the body is closed, as in Figure 1, there is only a single continuous vertical line apparent between the doors and panels.

I prefer to mount the glass of each of the 95 panels in a metal frame 42 (Fig. 10), generally H-shaped in cross section and embracing the edge of the glass on one side and a pro-

jecting rubber weather strip 44 at the other side. The panels 38 and 40 are not intended to overlap, but when closed as in Figure 1, are in substantially the same plane with the 5 narrow space between them sealed by the weather strips 44. The weather strips also seal the space between the bottom of the panel and the top edge of the door, and the space between the top edge of the panel and the horizontal projecting part of the top 22. The top 22 is provided with a downwardly projecting horizontal ledge or flange 46 against which the upper edges of the panels close. Preferably the panels are tilted slightly forward on the doors, their upper edges engaging the ledge 46 before the doors are quite closed, so that the panels are held against the ledge under some tension to prevent any possibility of rattling.

20 Each of the panels has a pair of downwardly projecting supporting posts 48 seated in sockets 50 in the top edge of the door. A rock shaft 52 is arranged in the top of the door and parallel to its upper edge with 25 cam portions 54, shown as being half-round in cross section, intersecting the sockets 50 when in operative position to grip the supporting posts of the panel. One cam portion 54 is shown in its inoperative position in 30 Figure 7; by turning the shaft 52 through a comparatively small angle, part of this cam portion is projected far enough into the socket to grip the supporting post very firmly. As shown in Figure 8, the shaft 52 may be 35 rocked by an arm 56 keyed thereto and engaged by an eccentric 58 on a swinging operating arm 60. The arm 60 is shown in its operative position in Figure 8, that is, with the highest point of the eccentric 58 in engagement with the arm 56, so that the shaft 52 is rocked to project the cam portions 54 into the sockets to grip the supporting posts. By lifting the arm 60 the posts are released so that the panel can be removed.

40 As shown in Figure 9, the shaft 52 may be rocked, if desired by a threaded operating member 62 engaging a stationary threaded nut 64 and operatively connected to an arm 65 keyed to the shaft.

45 The panels, when not in use, are intended to be housed in recesses formed in the doors themselves. As explained above, each panel is of the same width as the top edge of its door, and one feature of my invention relates to providing an offset portion or extension 66 on each door projecting beyond the axis of the door hinges 68, and into which extension 55 the recess for the panel extends, so that each panel may be fully housed within the door 60 notwithstanding the fact that it is as wide as the door when viewed from the outside of the car. The inside facing of the door may be cut away as indicated at 70 in Figure 3, to 65 facilitate withdrawing and inserting the panels.

While one illustrative embodiment has been described in detail, it is not the intention to limit the scope of the invention to that particular embodiment, or otherwise than by the terms of the appended claims.

70 I claim:

1. A vehicle door having sockets at its upper edge, a panel having supporting posts extending into the sockets, a rockshaft having cams intersecting the sockets to grip 75 the posts, and means for rocking the shaft.

2. A vehicle door having sockets at its upper edge, a panel having supporting posts extending into the sockets, a rockshaft having cams intersecting the sockets to grip the posts, 80 an operating arm on the rockshaft, and a pivoted member movable at right angles to the door and which has an eccentric part engaging the arm, the high point of the eccentric engaging the arm when said member is adjacent the door, so that the panel is released by swinging said member away from the door.

3. A hinged vehicle door formed on its inner side with a storage space extending as an offset past the hinged edge of the door, and 90 a panel of the same width as the outside width of the door sliding from the free edge of the door into the storage space.

4. A vehicle body having a pair of doors hinged at opposite edges and substantially 95 meeting at their free adjacent edges when closed, a door post between the doors against which the doors close, the free edges of the doors being rabbeted to overlap and conceal the post, said doors being formed on their inner sides with storage spaces extending as offsets past the hinged edges of the doors, and panels adapted to be housed in said offsets or mounted on the tops of the doors, said panels being of the same width as the doors so that 100 when in position they appear as continuations of the doors.

5. A vehicle door having sockets at its upper edge, a panel having supporting posts extending into the sockets, a rock shaft having means projecting into the sockets and adapted to grip the said posts when the rock shaft is rocked, and means for rocking the shaft.

6. A vehicle body having a pair of doors hinged at opposite edges and substantially meeting at their free adjacent edges when closed, a door post between the doors against which the doors close, the free edges of the doors being rabbeted to overlap and conceal the post, and a shiftable panel adapted to be mounted on the top of each door and have its edges substantially in vertical alignment with the lateral edges of the door, said doors being provided with laterally offset pockets for 115 housing the panels when not in use.

7. A vehicle door, means for pivotally mounting the door on the vehicle, a panel of the full width of the door and arranged to be shifted to a position to form a continuation 120

of the door in line therewith at its lateral edges, said door being provided with a pocket offset laterally toward the pivot for receiving the panel when not in use.

5. 8. A vehicle body member having a socket at its upper end, a supporting post fitting in the socket, a horizontal rock shaft mounted

in the body member and having means for gripping engagement with the supporting member to hold it in the socket, and cam ¹⁰ means for rocking the shaft to lock the supporting member in position.

In testimony whereof I affix my signature.

ROSCOE BERINGER.
